CLAIM

The ornamental design for a container body, as shown and described.

DESCRIPTION

FIG. 1 is a top, front, and left side perspective view of a coin holder for an automobile dashboard showing my new design with the roll top in closed position;

FIG. 2 is another top, front, and left side perspective view thereof with the roll top in open position and the magnet bottom cover shown in exploded view;

FIG. 3 is a top plan view thereof;

FIG. 4 is a right side elevational view thereof; and,

FIG. 5 is a bottom plan view thereof.

The rear of the design is unornamented.

**REEXAMINATION CERTIFICATE
ISSUED UNDER 35 U.S.C. 307**

THE PATENT IS HEREBY AMENDED AS
INDICATED BELOW.

AS A RESULT OF REEXAMINATION, IT HAS
BEEN DETERMINED THAT:

5 Claim 1 is cancelled.
